UNITED STATES PATENT OFFICE.

HIROJI KAMIJO, OF TOKYO, JAPAN.

MANUFACTURE OF CLOTH TAGS.

Application filed August 14, 1920. Serial No. 403,532.

To all whom it may concern:

Be it known that HIROJI KAMIJO, a subject of the Emperor of Japan, residing at No. 1 Gokencho, Kanda-ku, Tokyo, Japan, 5 has invented certain new and useful Improvements in the Manufacture of Cloth Tags, of which the following is a specification.

My invention relates to the manufacture 10 of cloth tags. According to my invention one part of a cloth is perfectly woven forming the body of the tag, while from the other part is omitted either the warp or weft thread, this part therefore being left un- 15 woven. This unwoven part is continuous with the woven part and is collected together to form binding strings. The object of the invention is to conveniently produce a cloth tag, of which the binding strings are strongly 20 combined with the body of the tag.

The invention will be more particularly described with reference to the accompanying drawings, in which by way of example Fig. 1 shows the fabric used for the manu- 25 facture of cloth tags according to one form of my invention; Figs. 2 and 3 show a tag cut from the fabric shown in Fig. 1 in half-finished and finished condition respectively. Fig. 4 shows the fabric used for the manu- 30 facture of cloth tags according to another form of the invention. Figs. 5, 6 and 7 show a tag cut from the fabric shown in Fig. 4 in unfinished, half finished and finished condition respectively.

35 In the texture, according to Fig. 1, the woven parts A consist of warp and weft threads, whereas the unwoven parts B consist of the weft thread only as shown, the parts A and B are alternately arranged. 40 The fabric is cut along the dash and dot lines so as to produce single tags of the size shown in Fig. 2, each such tag comprising a woven part a and an unwoven part b. The woven part a forms the body of the tag, while the 45 loose threads of the unwoven part b are collected together into strings c, thus producing the finished tag shown in Fig. 3.

In the fabric according to Fig. 4 the woven parts A' consist of weft and warp 50 threads, whereas the unwoven parts B' consist only of warp threads, the parts A' and

B' being alternately arranged like the parts A and B in Fig. 1. When the fabric is cut along the dash and dot lines, single tags like the one shown in Fig. 5 are obtained, each 55 comprising a woven part a and an unwoven part b. A portion of the loose warp threads b are removed, and the adjacent corners of the body part a are bevelled, as shown in Fig. 6. Then, the remaining loose warp 60 threads are collected together to form strings c, thus completing the tag as shown in Fig. 7.

Obviously, a tag manufactured according to this invention in which the body part a and the strings form an integral part not only has the advantage of being stronger than a paper tag and more pliant than a wooden tag, but the further special advantage is that the body part never can come off, 70 and that it requires no strings to be especially attached thereto.

I claim as my invention:

1. The method of making cloth tags which consists in producing a fabric comprising 75 alternating woven and unwoven parts, and then cutting the fabric into tag-size portions, each such portion comprising also a woven and an unwoven part.

2. The method as set forth in claim 1, in 80 which the loose threads of the unwoven part are twisted together to form strings for attaching the tag.

3. The method of making cloth tags which consists in producing a fabric of warp and 85 weft threads and comprising alternating woven and unwoven parts, the unwoven parts consisting of warp threads only, and then cutting the fabric into tag-size portions, each such portion comprising likewise a 90 woven and an unwoven part.

4. In the method as specified in claim 3 the further step of twisting together the loose warp threads into strings for attaching the tag. 95

5. In the method as specified in claim 3, the further steps of cutting out some of the outer loose warp threads, beveling the adjacent edges of the woven tag portion, and finally twisting the remaining loose warp 100 threads into strings for attaching purposes.

6. As an article of manufacture, a cloth

tag made of fabrics having a woven body part forming the tag proper and an unwoven part consisting of loose threads.

7. A cloth tag as specified in claim 5, in which the unwoven part consists of the loose warp threads of the fabric, which are twisted together into strings.

In testimony whereof I affix my signature in the presence of two witnesses.

HIROJI KAMIJO.
